DESIGN FOR A CHAIR

Joel D. Barber, New York, N. Y.

Application November 7, 1946, Serial No. 134,576

Term of patent 14 years

(CL. D15—1)

To all whom it may concern:

Be it known that I, Joel D. Barber, a citizen of the United States, residing at the city, county, and State of New York, have invented a new, original, and ornamental Design for a Chair, of which the following is a specification, reference being had to the accompanying drawing, forming part thereof.

The figure is a perspective view showing the chair according to my new design.

I claim:

The ornamental design for a chair, as shown.
JOEL D. BARBER.
